UNITED STATES PATENT OFFICE.

LARS HANSEN, OF KANSAS CITY, MISSOURI.

MOLDING-MACHINE.

1,348,411.

Specification of Letters Patent.

Patented Aug. 3, 1920.

Application filed April 21, 1919. Serial No. 291,695.

To all whom it may concern:

Be it known that I, LARS HANSEN, a citizen of the United States, residing in Kansas City, in the county of Jackson and State of Missouri, have invented a certain new and useful Improvement in Molding-Machines, of which the following is a specification.

My invention relates to improvements in molding machines. It relates particularly to machines adapted for making roofing tiles from cement or other plastic material.

One of the objects of my invention is to provide a molding machine which is provided with novel means for forming a transverse flange at one end of a tile and for forming holes in the tiles made by it adapted to receive securing devices for attaching the tiles to the roof.

Still another object of my invention is to provide a molding machine which will make tiles that will nest compactly, and with which the overlap, when laid on the roof, may be varied without danger of leakage.

The novel features of my invention are hereinafter fully described and claimed.

In the accompanying drawings, which illustrate the preferred embodiment of my invention,

Figure 1 is a plan view, partly broken away, of my improved machine, the die plate and forming tool being removed.

Fig. 2 is a vertical sectional view, partly broken away, taken on the plane of the line 2-2 of Fig. 1, the die plate and forming tool with a tile therebetween being shown.

Fig. 3 is a vertical sectional view, partly broken away, on the plane of the line 3-3 of Fig. 1, the die plate and forming tool being shown.

Fig. 4 is a view similar to Fig. 3, some of the parts being removed and the die plate shown elevated, the needles and the swinging flange forming member being shown retracted.

Fig. 5 is a vertical sectional view on the line 5-5 of Fig. 1.

Fig. 6 is a view partly in vertical section and partly in end elevation of the swinging flange forming member and parts connected therewith.

Fig. 7 is a plan view of four tiles, one partly broken away, such as are made with my machine, shown in operative relationship with each other.

Fig. 8 is a perspective view of one of the

completed tiles with the two diagonally opposite corners broken off.

Fig. 9 is a perspective view of the forming tool.

Fig. 10 is a sectional view on the broken line 10-10 of Fig. 7.

Fig. 11 is a fragmental longitudinal sectional view of a tile, showing the hole formed by the central U-shaped needle.

Fig. 12 is a top view of the die plate.

Fig. 13 is an end view of some of the tiles, showing how the tiles fit together.

Similar reference characters designate similar parts in the different views.

The frame of the machine comprises preferably a table having a box top 1 and four legs 2. Two longitudinal guide plates 3 disposed edge up, have their lower edges supported on vertical screws 4, Fig. 2, fitted in threaded holes in the bottom of the table top 1. By adjusting the screws 4, the guide plates 3 may be vertically adjusted to a desired height, in which position they may be held by clamping plates 5 fastened to the top 1 by bolts 6, Fig. 1.

On the top 1 between the guide plates 3 and spaced apart from the guide plates is a rectangular mold frame 7, to the inner sides of which are respectively secured by bolts 8, vertically adjustable side mold members 10 and end mold members 11, having slots 9 through which the bolts 8 extend, said bolts being fitted in threaded holes in the sides of the mold frame 7.

Between the mold members 10 and 11 is a removable die plate 12, Figs. 2, 3, 4 and 12, the upper side of which forms the under side of a cement tile 13, the upper side of which is formed by a hand operated forming tool 14, having on its under side adjacent to its ends bearing surfaces 15 adapted to rest upon the upper edges of the guide plates 3, Figs. 2 and 9.

The under side of the central portion of the forming tool 14 corresponds in contour to the upper edges of the end mold members 11, so as to permit the tool to pass across them.

The tool 14 between the guide plates 3 and the central tile forming portion is provided with hand holds 16, the outer ends of which terminate at downwardly extending projections 17, adapted to respectively slidably engage the inner sides of the guide plates 3.

The upper edges of the guide plates 3 and

the bearing surfaces 15 are horizontal, while the under side 19 of the central portion 18 of the forming tool inclines upwardly to the left, as shown in Fig. 3, and is sharp at its 5 forward or left edge, as viewed in Fig. 3, so that the tool will cut away the excess cement and sand, while the inclined lower side 19 will pack and smooth the top of the tile 13.

10 For supporting the die plate, 12, in operative position, shown in Figs. 2 and 3, there are provided between the mold members 10 and 11, four vertical screws 20, Figs. 1, 2, 3, and 4, which are fitted in threaded holes 15 in the top 1 and are respectively provided with lock nuts 21, which bear against the top 1.

15 For lifting the die plate 12 with the completed tile 13, above the mold members 10 and 11, so that the die plate and tile may be easily removed, there are provided two vertical slideable inverted U-shaped members 22 and 26, the transverse portions of which support the die plate 12. The lower ends of 21 the member 22 are respectively pivoted to the arms of a U-shaped lever 23, the arms of which are pivoted by horizontal bolts 24 to the arms of an inverted U-shaped bracket 25 secured to the under side of the top 1. 25 The arms of the member 26 are vertically 30 slideable in holes in the top 1, and below the top are pivoted respectively to the arms of a U-shaped lever 27, the arms of which are 35 respectively pivoted by horizontal bolts 28 to an inverted U-shaped bracket 29 secured to the under side of the top 1.

40 For swinging the levers 23 and 27, so as to lift the members 22 and 26 and the die plate 12, I provide a horizontal shaft 30, Figs. 3 and 4, having a crank 31, Fig. 1, and oscillatable in bearings 32 depending from the table top 1. The rock shaft 30 is provided with two cam arms 33, Figs. 2, 3 and 4, which are adapted, when the shaft 30 is 45 turned, counter-clockwise, as viewed in Figs. 3 and 4, to strike the under sides respectively of the arms of the levers 23 and 27, thereby, on continued turning of the shaft 30 to the position shown in Fig. 4, lifting 50 the die plate 12 and the formed tile 13 above the mold members 10 and 11.

45 For forming on the upper side of the tile 13 at one end thereof an arcuate transverse flange 34, Figs. 3, 4 and 8, I provide a mold member 35, which has secured to its outer side two plates 36, each of which is provided with an outwardly extending horizontal projection 37, Figs. 3, 4 and 6, provided 60 with a vertical hole, through which slidably extends one of two pins 38, which are rigidly secured at their lower ends to a horizontal rack bar 39, which has its ends respectively pivoted on two horizontal screws 40 adjustably mounted in opposite sides of 65 the frame 7.

When the rock bar or shaft 39 is rocked in the proper direction, the mold member 35 is moved from the operative position shown in Fig. 3, to the position shown in Fig. 4, 70 thus permitting the removal of the tile 13.

For securely holding the mold member 35 in the operative position, each plate 36 is provided with an outwardly extending projection 41 adapted to be engaged on its upper side by the inwardly turned end 42, 75 on the upper end of the adjacent rod 38.

For oscillating the rock shaft 39, it is provided with a downwardly extending crank arm 43, Fig. 5, which has its lower end pivoted to one end of a link 44, the other end of which is pivoted to a crank 45 provided on the rock shaft 30. The arrangement is such that when the rock shaft 30 is swung from the position shown in Fig. 3 to that shown in Fig. 4, the mold member 80 85 35 will first be swung so as to clear the adjacent inner side of the mold member 11, after which the cam arms 33 will swing the levers 23 and 27 so as to lift the die plate 12 to the elevated position shown in Fig. 4.

90 For forming a hole 46, Fig. 4, in one end of the tile 13, I provide a needle 47, which is pivoted on a horizontal axis to the upper end of a screw 48, the lower end of which is fitted in a threaded hole in the rock shaft 95 39, to which the screw is locked by means of a lock nut 49.

95 The needle 47 is adapted to slide in a transverse hole 50, Fig. 4, provided in the adjacent mold member 11, from the position 100 shown in Fig. 4, to that shown in Fig. 3, in which position the needle 47 extends inwardly beyond the mold member 11 and against a shoulder on the upper side of the die plate 12. When in this position, the 105 cement forms around the needle 47, and when the latter is withdrawn, to the position shown in Fig. 4, the needle will be withdrawn from the tile, thereby forming the hole 46, through which a nail or other 110 securing device may be inserted for attaching the tile to the roof. By having the needle 47 pivoted to its support, the needle slides in the hole 50, thus keeping the hole clear of cement. By pivoting the needle 115 47 to the vertically adjustable screw 48, the position on the rock shaft 39 of the needle may be varied to adapt it for different thicknesses of tile, the thickness of the tile being dependent upon the adjustment of the 120 screws 20, which support the die plate 12 in operative position.

125 For forming a hole 51, Figs. 10 and 11, in the under side of the tile 13, near the middle thereof, I provide a U-shaped needle 52, Fig. 5, which is clamped at its lower arm between two vertical plates 53, the lower ends of which are pivoted on a horizontal axis to one end of a link 54, the other end of which is pivoted to the crank 43. 130

The plates 53 are pivoted on a horizontal axis and intermediate of its ends to and between the two arms of a U-shaped plate 55, which has its transverse portion resting 5 on the top 1 and has its ends resting upon a vertical screw 56 which is adjustably fitted in the top 1, Fig. 5. By adjusting the screw 56, the plates 53 carrying the needle 52 may be vertically adjusted. A vertical screw 57 10 fitted in a threaded hole in the top 1 and extending between the arms of the plate 55 has its head bearing against the upper edges of said arms, so as to securely hold the plate 55 in the position to which it may be adjusted. 15

The upper arm of the needle 52 has the form of an arc, the center of which is the axis of the plates 53 in the plate 55.

The needle 52 is adapted to enter a hole 20 58 provided in the die plate 12, Fig. 12, which communicates with a transverse depression 59 provided in the upper side of the die plate 12, for receiving tile material. As shown in Fig. 5, the adjacent end of the 25 needle 52 is adapted to strike the opposite wall of the depressed portion 59. When the needle is in the position shown in Fig. 5, the tile material will fill the depression 59 around the needle 52. When the needle is 30 withdrawn, it will leave a hole which extends through the lug 60, Fig. 11, formed on the lower side of the tile 13 by the depression 59.

The upper side of the die plate 12 adjacent to one corner has an oblique rib 61, Fig. 12, which forms a groove in the under side of the tile 13, whereby the tile is weakened so that the corner may be easily broken off, as shown in Figs. 7 and 8.

The upper side of the die plate 12 adjacent to the corner diagonally related to the rib 61 is provided with a rib having an oblique portion 62, which at its inner end connects with a longitudinal rib portion 63, 45 whereby the tile is so weakened that the adjacent corner may be readily broken away.

The upper side of the die plate 12 is provided with a transverse raised portion 64, which forms a transverse groove 65 in the 50 under side of the tile 13, said groove being much wider than the thickness of the arcuate flange 34 on the upper side of the tile 13 at the end distant from that having the groove 65.

When the tiles are fitted together, as shown in Fig. 7, the flange 34 of the lower tile fits in the groove 65 of the tile next above. The groove 65 being wider than the flange 34, longitudinal adjustment of one 55 tile relatively to the one next above or below may be obtained. By having the diagonal corners obliquely broken away, as shown, the overlap of the tiles may be varied to a considerable amount, to correspond with the distance between the roofing strips to which

the tiles are secured. At the same time, the joints will be covered so that leakage will be avoided.

In the operation of my invention, the initial position of the parts excepting the forming tool 14, will be as shown in Fig. 3. Sufficient tile making material is then placed on the die plate 12, after which the forming tool is employed to pack the material under the mold member 35 so as to form the flange 70 34, on the upper side and one end of the tile 13. After this has been done, the forming tool 14 is moved away from the mold member 35, and being slid on the guide plates 3, its sharpened forward edge removes excess 75 material and pushes it forwardly, while the inclined under side 19 of the forming tool 80 smooths and properly forms the upper surface of the tile.

The crank shaft 30 is then turned counter-clockwise, as viewed in Figs. 3 and 4, thereby by swinging the needles 47 and 52 out of the formed tile by the mechanism already described. At the same time, the mold member 35 will be moved to the position shown in Fig. 4. Continued turning in the same direction of the rock shaft 30 will cause the cam arms 33 to swing the levers 23 and 27 to the position shown in Fig. 4, thereby lifting the die plate 12 and tile 13, by means 90 of the members 22 and 26, to the position shown in Fig. 4.

Upon retracting the rock shaft 30, to the initial position shown in Fig. 3, the levers 100 23 and 27 will swing downwardly by gravity, thus lowering the members 22 and 26 and a new die plate carried thereby, the die plate being deposited between the mold members 10 and 11 upon the screws 20. At this time, the mold member 35 and the needles 47 and 52 will move into the operative 105 position shown in Figs. 3 and 5.

By having the mold members 10 and 11, the guide plates 3 and the screws 20 vertically adjustable, compensation for wear due 110 to the sliding back and forth of the tool 14 will be afforded.

By having the guide plates 3 spaced a considerable distance from the mold frame 7, 115 said plates will be clear of cement and sand, thus greatly reducing wear upon them.

I do not limit my invention to the structure shown and described, as many modifications, within the scope of the appended claims, may be made without departing from 120 the spirit of my invention.

What I claim is:—

1. In a molding machine, a supporting frame, a stationary mold member mounted on said frame, a rock shaft oscillatable in 125 said frame, a swinging mold member carried by the rock shaft and movable to and from an operative position projecting inwardly beyond the upper edge of the stationary mold member, means for oscillating 130

- the rock shaft, and a forming tool slidable on said frame over the die plate to and from a position against and extending below said swinging mold member when the latter is in 5 the inwardly projecting position.
2. In a molding machine, a supporting frame, a stationary mold member mounted thereon, a rock shaft oscillatable on said frame and having an upwardly extending rod, a swinging mold member carried by said rod and movable therewith to and from an operative position projecting inwardly above and beyond the upper edge of the stationary mold member, and means for oscillating the 10 rock shaft.
3. In a molding machine, a supporting frame, a stationary mold member mounted thereon, a rock shaft oscillatable in said frame and having an upwardly extending rod, a swinging mold member carried by and 15 slidable on said rod and movable therewith to and from an operative position projecting inwardly above and beyond the upper edge of the stationary mold member, the rod having means for limiting the upward sliding movement of the swinging mold member, and means for oscillating the rock shaft.
4. In a molding machine, a supporting frame, a stationary mold member mounted 20 thereon, a rock shaft oscillatable in said frame, a needle pivotally mounted on the rock shaft and adapted, when the rock shaft is oscillated to move to and from a position in which it will extend through and project 25 inwardly beyond the inner side of the stationary mold member, and means for oscillating the rock shaft.
5. In a molding machine, a supporting frame, a stationary mold member mounted 30 thereon, a rock shaft oscillatable in said frame, a needle supporting member radially adjustable in said rock shaft, a needle pivoted to said needle supporting member and adapted, when the rock shaft is oscillated, 35 to move to and from a position in which it will project inwardly beyond the inner side of said mold member, and means for oscillating said rock shaft.
6. In a molding machine, a supporting 40 frame, a stationary mold member mounted thereon, and having a transverse hole, a die plate adapted to be supported in operative position at the inner side of the mold member, a rock shaft oscillatable in said frame, a 45 needle support carried by said rock shaft, a needle pivoted to said needle support and adapted, when the rock shaft is oscillated, to move to and from a position in which it will extend through said hole to a point at 50 the inner side of the mold member and have 60 its inner end resting against said die plate, and means for oscillating said rock shaft.
7. In a molding machine, a stationary mold member having a hole therethrough, a rock shaft, needle supporting means carried 65 by and radially adjustable on the rock shaft, and a needle pivoted to said needle supporting means and movable thereby, when the rock shaft is oscillated to and from a position in which it will extend through said hole and beyond the inner side of the mold member.
8. In a molding machine, a stationary mold member having a hole therethrough, a rock shaft, a screw radially adjustable in 70 said rock shaft, and a needle pivoted to said screw and movable thereby to and from a position in which it will extend through said hole and beyond the inner side of said mold member.
9. In a molding machine, a supporting frame having guides, upright mold members supported by said frame, means adapted to support a die plate in operative position between said mold members, a swinging 75 mold member movable over said die plate to and from a position extending over the upper edge of one of said mold members, and a forming tool slidable on said guides over the die plate to and from a position 80 against and extending below said swinging mold member when the latter is in the extending over position.
10. In a molding machine, a supporting frame, a mold member mounted thereon, 85 means adapted to support a die plate in operative position at the inner side of said mold member, a swinging mold member movable to and from a position over the die plate and at the inner side of said mold member, means 90 for swinging said movable mold member to and from said position and for lifting the die plate, and a forming tool slidable on said frame over said die plate to and from a position against and extending below said 95 swinging mold member when the latter is over the die plate.
11. In a molding machine, a supporting frame, a stationary mold member mounted 100 thereon, a swinging mold member movable to and from a position at the inner side of the stationary mold member, and a forming tool movable on said frame toward and from said mold members and having its lower side 105 lower than the swinging mold member.
- In testimony whereof I have signed my name to this specification.
- LARS HANSEN.
